Primary Examiner — Cynthia R Underwood(74) *Attorney, Agent, or Firm* — Nelson Mullins Riley & Scarborough LLP; Anthony A. Laurentano(57) **CLAIM**

The ornamental design for a bread box blank, as shown and described.

DESCRIPTION

FIG. 1 is a top isometric view of a bread box blank showing our new design;

FIG. 2 is a bottom isometric view of the new design;

FIG. 3 is a top plan view of the new design;

FIG. 4 is a front side edge view of the new design, and the rear side edge view is identical;

FIG. 5 is a left side edge view of the new design, and the right side edge view is identical; and,

FIG. 6 is a bottom plan view of the new design.

The broken lines depict fold lines and are part of the claim. The dot-dash-dot lines indicate unclaimed portions of the claimed design and form no part of the claim.

1 Claim, 4 Drawing Sheets(56)
